WIRE STRETCHER

George T. Thompson, Lake City, Colo.

Application September 25, 1939, Serial No. 296,507

2 Claims. (Cl. 254—80)

The object of this, my present invention, is the provision of a wire stretching tool to be used primarily in stretching line wires, for fences, or fabric fencing and the object of the invention is 5 the provision of a tool for this purpose which is of an extremely simple nature, and which includes a lever member having a stationary jaw and a pivoted jaw, movable, when fulcrumed against a fence post toward the stationary jaw 10 and to effect a tight biting or gripping engagement of the jaws with the wire, so that the greater pressure exerted upon the tool the greater will be such biting engagement of the fences by the jaws.

15 A further object is the provision of a tool for this purpose in which the movable jaw will be moved toward or away from the stationary jaw by the manipulation of a grip member which is associated with the lever of the tool and has a 20 connection with the movable jaw.

To the attainment of the foregoing the invention consists in the improvement hereinafter described and definitely claimed.

In the drawing:

25 Figure 1 is a perspective view of the improvement.

Figure 2 is a perspective view of the improvement with the parts disassembled.

30 Figure 3 is a perspective view of the swingable jaw.

Referring now to the drawing in detail the numeral 1 designates the lever of the improvement.

The lever is in the nature of a strong metal plate and has one of its ends formed with a handle 35 portion 2. The lever, adjacent to its second end has fixed upon its opposite faces the inner arms 3 the ends of which are extended laterally, as at 4, and the said extensions have their outer edges toothed, as at 5. The members 4 provide the 40 stationary jaws of the improvement. The swingable jaw comprises a member which consists of two metal plates 6 which are spaced from one another throughout a portion of their length and contact one another throughout another portion.

45 The arms at their outer or connected ends are arched and curved rearwardly, as at 7, and the second ends of the arms are formed with angle extensions 8 whose inner edges are toothed, as at 9. The arms 6 receive therebetween the outer 50 end of the lever 1 and the said arms are pivoted to the lever, as indicated by the numeral 10. Pivoted, as at 11, between the swingable jaw members 8 there is the flat end 12 of a rod 13. The second end of the rod is bifurcated and is 55 pivotally secured to an ear 14 that depends from

a grip or handle member 15. The end of the member 15 is offset opposite the ear 14, as at 16, and is bifurcated. The bifurcated portion of the member 15 receives therein the lever 1, adjacent to the handle member 2 thereof and a pivot 17 5 passes through the offset bifurcated portion 16 of the grip or handle member 15 and through the lever.

The handle member 15 is only swung toward the lever when a wire strand 18 is to be held between the jaws, and prior to the stretching of such strand over a fence post 19. When in stretching position the arched or curved end 7 of the arms or body portion of the swingable jaw 8 is brought against the fence post so that the said 15 post serves as a fulcrum element. The lever is 20 swung in the direction of the arrow disclosed by Figure 1 of the drawing which will obviously cause the jaws 6 to be moved toward the stationary jaws 4, and as a result the wire strand 20 18 may be stretched along the post in an easy and positive manner.

It is believed the foregoing description will 25 fully and clearly set forth the construction, operation and advantages of my improved device but obviously I do not wish to be restricted to the specific structure herein shown and described and, therefore, hold myself entitled to 30 make such changes therefrom as fairly fall within the scope of what I claim.

Having described the invention, I claim:

1. A lever having a laterally extending fixed jaw thereon, a swingable jaw pivotally secured to the lever and disposed opposite the fixed jaw, said swingable jaw having an arm extension, a 35 rod member pivotally secured to the swingable jaw, and a handle member pivotally secured to the lever and to the rod member.

2. A lever, a pair of fixed jaws on the lever and having laterally extending ends the outer 40 ends of which are toothed, a member consisting of two metal plates being spaced from one another throughout a portion of their length and contacting one another throughout another portion forming a swingable jaw pivoted to the lever, 45 said member having its outer ends arched and its inner ends formed with lateral extensions the outer edges of which are toothed and which extensions provide jaws that are arranged opposite the first named jaws, a rod guided between the 50 fixed jaws and pivotally secured between the swingable jaws, and a handle pivoted on the lever and to which handle the rod is pivoted.
